C. HAMANN

BOTTLE WASHER

Filed Jan. 30, 1919

Inventor
Charles Hamann
by E. M. Bentley
Attorney

UNITED STATES PATENT OFFICE.

CHARLES HAMANN, OF PORT CHESTER, NEW YORK.

BOTTLE WASHER.

Application filed January 30, 1919. Serial No. 274,116.

To all whom it may concern:

Be it known that I, CHARLES HAMANN, a citizen of the United States, residing at Port Chester, county of Westchester, State of New York, have invented certain new and useful Improvements in Bottle Washers, the following being a full, clear, and exact disclosure of the one form of my invention which I at present deem preferable.

For a detailed description of the present form of my invention, reference may be had to the following specification and accompanying drawings, forming a part thereof, in which—

Fig. 1 is a plan view of my machine;

Fig. 2 is a side elevation partly in section;

Fig. 3 is a horizontal section, and

Fig. 4 shows the bottle-belt adjustment.

My invention relates to bottle-washing machines of the general type shown in my Patents Nos. 1,241,508 and 1,269,077, and involves certain improvements therein which have proved of substantial value and which will be described in detail herein and specified in the claims.

Referring to the drawing, A represents a horizontal receptacle in the form of a metal bowl which is mounted on suitable legs and forms the base portion of the machine. In the rear, and shallower, portion of bowl A is placed a vertical column B which carries at its upper end a horizontal receptacle in the form of a pan C which contains the primary driving mechanism and keeps the oil and dirt incident to such mechanism away from the washing apparatus beneath. On the bottom of the bowl is fixed a stud E on which rotates the bottle-carrier D driven by a gear wheel F engaged by pinion F¹. The bottle-carrier is of a well known form, being hollow to allow for a water jet to be directed into the bottle I and requires no detailed description. The stud E carries an adjustable step bearing G for the shaft G¹ of the rotary brush H which acts on the outside of the bottles as it, and also the bottles, are rotated. In the pan C are mounted

the fast and loose pulleys K, K¹ that receive the main driving belt. The driving pulley operates a bevel pinion L meshing with a bevel gear L¹ on the upper end of a shaft which passes down through the aforesaid column B and, by means of a chain-belt M, operates the pinion F¹. On the same shaft

with gear wheel L¹ is a sprocket wheel N, which drives the aforesaid shaft G¹ by means of a sprocket wheel O and a chain belt, this belt being kept in tension by an adjustable idler wheel P¹. The same chain belt also drives, by means of sprocket wheel P, the vertical shaft S on which is the pulley Q for the bottle-belt T. The said bottle-belt passes horizontally over the said pulley Q and over a companion pulley Q¹, as is shown in Fig. 3. Between pulleys Q and Q¹ this belt passes over certain of the bottles I, rotating them on their own axes and also pressing them against the brush H. The tension of said belt T is adjusted by means of the flexible mounting of the aforesaid pulley Q¹, which mounting is shown in Fig. 4. On one side of the pan C is fixed a bracket arm R (see Figs. 1, 2, 4) through the outer end of which passes the vertical bar V in which there is a U-shaped bend or offset V¹. The pulley Q¹ is mounted in the two jaws of a yoke W which is contained in the bend V¹ and is free to slide in and out with respect thereto, being mounted on slideways v, v thereon and having a rear stud Y which extends through the vertical part of the bend. A compression spring X acts to press the yoke, and the pulley carried thereby, outwardly from the bend V¹. That tends to force the pulley Q¹ away from the pulley Q and thereby put tension on the belt T. At the same time the angular direction of the spring-movement of the pulley Q¹ may be adjusted by swinging the bend V¹ with respect to the bracket R. Thus the pressure of the belt on the bottles, as well as the belt tension, is maintained and adjusted.

What I claim as new and desire to secure by Letters Patent is:

1. A bottle-washing machine comprising upper and lower receptacles, a column connecting the two receptacles, a circular bottle carrier over the lower receptacle, driving mechanism therefor, primary driving mechanism for the machine mounted in the upper receptacle, said driving mechanisms being connected, a brush wheel concentric with the bottle carrier, a belt for rotating the bottles, and means for actuating the belt.

2. A bottle-washing machine comprising upper and lower receptacles, a shaft passed through both receptacles, a bottle carrier mounted over the lower receptacle and actuated by said shaft, a primary driving shaft mounted in the upper receptacle and geared to the contiguous end of the first mentioned

shaft, a brush wheel mounted over said bottle carrier, mechanism operatively connecting said brush wheel and said first mentioned shaft, a bottle engaging belt, means whereby movement is imparted thereto, means in the upper receptacle for actuating said movement imparting means, and means for maintaining a tension on said belt.

3. A bottle-washing machine comprising 10 a receptacle having a shallow portion and a deeper portion, a column in said shallow portion, an upper receptacle supported by said column, bottle cleaning apparatus mounted in the lower receptacle, and driving mechanism located in said upper receptacle, whereby the cleaning apparatus is protected from oil and dirt normally adhering to the driving mechanism.

4. A bottle-washing machine comprising 20 a base portion shaped to provide a lower receptacle, a bottle cleaning apparatus mounted therein, a column located within said receptacle and having its lower end secured thereto, an upper receptacle supported 25 by said column, a shaft passed through said

column, a carrier located within the lower receptacle and operatively connected with the lower end of said shaft, primary driving mechanism in the upper receptacle geared with the contiguous end of said shaft, a brush wheel operatively connected with the upper end of said shaft, and a bottle engaging belt also operatively connected with said shaft.

5. A bottle washer comprising a lower 35 receptacle, an upper receptacle, bottle cleaning mechanism including a bottle rotating belt, located between said receptacles, pulleys for said belt, a bracket interposed between said receptacles, a yoke slidably mounted in 40 said bracket, one of said pulleys being mounted in said bracket, and driving mechanism located in said upper receptacle, whereby the cleaning apparatus is protected from oil and dirt normally adhering to the driving mechanism.

Signed at New York city, N. Y., January 28th, 1919.

CHARLES HAMANN.
